UNITED STATES PATENT OFFICE.

FERDINAND A. WATTENBERG, OF NEW YORK, N. Y.

MATCH-BOX.

SPECIFICATION forming part of Letters Patent No. 729,818, dated June 2, 1903.

Application filed March 7, 1903. Serial No. 146,777. (No model.)

To all whom it may concern:

Be it known that I, FERDINAND A. WATTENBERG, a citizen of the United States, residing at New York, borough of Manhattan, county 5 and State of New York, have made a new and useful Invention in Match-Boxes, of which the following is a specification.

My invention is directed particularly to an improvement upon an invention disclosed in 10 a prior application filed by me in the United States Patent Office on the 17th day of March, 1902, and bearing Serial No. 98,695.

In the invention disclosed in the above-named application I have described and 15 claimed as a means for igniting safety-matches a cup or casing filled with material for effecting such a result. I have also described and claimed a match-box having a depressed groove in combination with a cup or casing 20 filled with such material.

The essential feature of the present improvement lies in doing away entirely with the cup or casing and constructing the igniting material in a mass in the nature of a 25 solid bar, rod, or cake, and then in combining the same with a match-box having a groove or depression for receiving the bar, rod, or cake of sufficient width to admit the head of the match and of sufficient depth to prevent 30 the surface of the material from coming into contact with the fingers or clothing of the user.

My improvement will be fully understood 35 by referring to the accompanying drawings, in which—

Figure 1 represents a rectangular-shaped bar constructed of the proper material for igniting safety-matches, and Fig. 2 is a perspective view of a pocket match-box illustrating 40 my invention.

I am aware that it is old in the art to provide a match-box with an igniting-surface for safety-matches, in which the same is composed of a sheet of paper having a coating of 45 material for igniting safety-matches pasted or painted thereon, such a device being disclosed in United States Patent No. 120,892, granted November 14, 1871, to L. O. Myers, and I am also aware that it is broadly old in the art to 50 construct a bar or block of igniting material for safety-matches composed of phosphorus and any suitable binding agent and to use

said bar or block in connection with a table, counter, or wall match-box in which there is necessarily a large exposed surface of the 55 material. Such match-boxes, however, are not handled frequently by the users, and consequently the material which constitutes the striking-surface and is known to be very poisonous and dangerous to handle does not 60 come into contact with the hands or clothing of the user.

My present improvement is directed especially to pocket match-boxes, which are carried on the person of the user and always manipulated or handled during the striking of a match, so that unless the surface of the material be held in a depressed position and in such a way as to keep it out of contact with the fingers of the user there is danger of transmitting the poisonous material to the fingers 7c and from the fingers to the eyes, which is known to be very dangerous.

My present invention is specifically an improvement upon the invention disclosed in 75 my prior application, in that I do away, as above indicated, with the cup or casing which holds the igniting material and simply insert a rod, bar, or cake of the igniting material into the depressed groove in the match-box. 80

For a full and clear understanding of my improvement, such as will enable those skilled in the art to construct and use the same, reference is now had to the drawings in detail, in which—

A represents a bar constructed of igniting material, such as is used for the purpose of igniting safety-matches. In the construction of this bar I have ordinarily used the liquid igniting material for safety-matches, such as 90 is found upon the market and is used by all large manufacturers of safety-matches, by painting or pasting a thin coat of the same upon the body of the box. I have heretofore taken this material and evaporated or 95 boiled the liquid until it assumed a thick or pasty mass of the desired nature. Then by pressure I formed it into bars or cakes, like that disclosed in Fig. 1 of the drawings, and afterward subjected it to a drying process, 100 either in the open air or by heat from a stove, or I have taken the paste-like material and subjected it to the action of a rectangular-shaped die, so as to form the bar of the de-

sired cross-section, and have cut it into such lengths as the necessities of the case might demand. The material as thus constructed in solid cake-like form is ready for use when-

5 ever needed.

In Fig. 2 I have illustrated a pocket match-box B, having a spring-actuated cover C of well-known form, and in one side or edge of the box a groove G is formed in such manner 10 as to constitute an open-sided pocket or chamber adapted to receive the bar A of igniting material, the lateral edges of the groove being sufficiently depressed to prevent the material A from coming into contact with the 15 fingers or clothing of the user. The width of the groove G is preferably such as will just freely admit the heads of the matches now found in commercial use, so that they will come into contact with the igniting material 20 when drawn thereover. This feature, in so far as the construction of the box is concerned, is not materially different from that disclosed in my prior application, except that in that case the bottom of the groove was done away 25 with, the bottom of the cup or casing constituting the necessary dividing-partition be-

tween the igniting material and the matches in the box. In the present instance, therefore, it is necessary to provide a bottom to the groove, which acts as a dividing-partition between the material A and the interior 30 of the box B, where the matches are located.

Having thus described my invention, what I claim, and desire to secure by Letters Patent of the United States, is—

35 A solid bar, rod or cake of igniting material for igniting safety-matches; in combination with a match-box having a groove or depression for receiving the same, the lateral edges of said groove being so disposed as to 40 prevent the igniting material, when in position, from coming into contact with the fingers or clothing of the user, substantially as described.

45 In testimony whereof I have signed my name to this specification in the presence of two subscribing witnesses.

FERDINAND A. WATTENBERG.
